MERCURY SWITCH

Arthur S. Dysart, Elizabeth, N. J., assignor of
one-half to Mabel S. Dysart, Elizabeth, N. J.

Application May 22, 1945, Serial No. 595,155

8 Claims. (Cl. 200—122)

1

This invention relates to mercury switches and particularly to switches of this type operated by variations in the pressure of a gas filled chamber forming part of the switch to move a quantity of mercury between contact closing and opening positions.

More particularly the invention relates to mercury switches in which a small quantity of mercury is forced through an orifice or along a channel into a position to electrically connect two terminals, movement of the mercury being effected by heating a chamber, closed except for the orifice, so that the air or gas within the chamber, being increased in volume by being heated, will force the mercury through the orifice into another chamber or portion of the switch to connect the terminals of a main or load circuit.

Any gas that will not combine with mercury may be used.

A primary object of the invention is to provide a pressure or heat operated mercury switch that will be simple, compact, and that will not easily get out of order.

A feature that enables the above object to be accomplished is that the parts employed in the switch are few in number and easily assembled in permanent relative positions within a sealed member.

With the above and other objects in view the invention includes the features of construction and operation set forth in the following specification and illustrated in the accompanying drawings.

In the accompanying drawings annexed hereto and forming a part of this specification, I have shown the invention embodied in several different types of liquid contactor switches, but it will be understood that the invention can be otherwise embodied and that the drawings are not to be construed as defining or limiting the scope of the invention, the claims appended to this specification being relied upon for that purpose.

In the drawings:

Figures 1, 3, 4, 5, 7, 9 and 10 are central longitudinal sectional views of mercury switches showing different embodiments of the invention.

Fig. 2 is a transverse sectional view of one form of the invention taken on the plane of line 2—2 in Fig. 1.

Fig. 6 is a transverse sectional view of another form of the invention taken on the plane of line 6—6 in Fig. 5.

Fig. 8 is a transverse sectional view of another form of the invention taken on the plane of line 8—8 in Fig. 7.

Fig. 11 is a transverse sectional view taken on the plane of line 11—11 in Fig. 10.

In the above-mentioned drawings there have been shown a number of different embodiments of the invention which are now deemed preferable for different conditions and services, but

2

it is to be understood that changes and modifications may be made within the scope of the appended claims without departing from the spirit of the invention.

5 Briefly, and in its preferred aspect, the invention may include the following principal parts: First, adjacent chambers communicating with each other by means of a connecting orifice or channel; second, a quantity of mercury movable from one chamber partially or wholly into the other; third, terminals mounted on each of the casings of the chambers; and fourth, means to heat or otherwise change the pressure of the gas in one or both chambers.

10 Referring more in detail to the figures of the drawings, and first to the embodiment of the invention shown in Figs. 1 and 2, it will be seen that two metal casings 10 and 12 fit partially one within the other and are held in their relative positions by insulating material such as rubber 14, etc. Surrounding a portion of the inner casing 10 and disposed within the inner end of the outer casing 12 is a channelled member of porcelain, or other insulating material, forming a firm body member 16. At the lowermost part of the inner casing 10 is a small aperture 18, the body member 16 being so formed adjacent this orifice 18 that a channel is formed from the interior of the inner casing 10 to the end wall of the outer casing 12. Mercury 20 within the casing 10 may therefore flow through the orifice 18 and between the sloping sides of the body member 16 to electrically connect the end walls of the casings 10 and 12 by this liquid conductor 20. Terminals 22 and 24 on the casings 10 and 12 are electrically connected when the mercury 20 is forced partially from the casing 10 and comes into contact with the casing 12.

15 To force the mercury 20 from the position shown in Fig. 1 into contact with the casing 12, a heating resistance 26 is provided within casing 10. When this resistance 26 is connected to a source of current as by a switch 28 connecting lead lines of a supply circuit, the heat increases the pressure and volume of the gas within the chamber of casing 10 and forces the mercury 20 partially or wholly from this chamber into contact with the end wall of casing 12. This connects terminals 22 and 24 electrically and closes the main circuit between terminals 22 and 24 of any type. Any excess gas will follow the mercury through orifice 18 into space 11 without breaking the continuity of the electric circuit. With the switch 28 opened the pressure within casing 10 will be reduced by cooling of the gas therein and excess pressure of the gas in the other chamber will return the mercury 20 to the position shown in Fig. 1 which will then open the circuit between the terminals 22 and 24.

20 Terminal screw 25 contains an axial hole 23

communicating with radial hole 27 near its inner end. Screw 25 is pushed into chamber 9 until radial hole 27 connects with chamber 9. A rubber tube (not shown) may be attached to the outer end of screw 25 and the switch chambers exhausted. The desired gas is then admitted into the switch through the same tube at the desired pressure, preferably higher than atmospheric pressure. Nut 31 is then set up tight, drawing the head of screw 25 against plug 33, closing the radial hole 27 and sealing the gas into the switch.

Fig. 3 illustrates a modification of the embodiment of the invention shown in Figs. 1 and 2. Inner and outer casings 10 and 12, the body member 16 within the outer casing, the terminals 22 and 24, etc., may all be similar to their corresponding parts shown in Figs. 1 and 2. Instead of the pressure within the inner casing 10 being increased by heating the gas therein, a bellows 30 is connected thereto as by a nipple 32. A hand lever 35 moved about a fixed pivot or axis compresses and expands the bellows 30 and thus increases and decreases the gas pressure within this casing 10 and forces the mercury 20 into contact with the outer casing 12 in the same manner as in Figs. 1 and 2. A transparent plug 17 provides a window through which the action of the switch may be seen.

Fig. 4 shows a still further method of increasing the pressure within one or the other of the casings 10 or 12 to force the mercury 20 to make and break an electrical connection between the casings. Surrounding one, or if desired both, of the casings, as in Fig. 4 are jackets 34 and 36 of any suitable material. Each of these jackets is provided with openings for the entrance and exit of a fluid. The fluid in one of the jackets may be heated or cooled to a different temperature from that in the other jacket, causing a difference in temperature between the casings 10 and 12. When a difference in temperature exists between the spaces in casings 10 and 12 the mercury 20 will be forced from one to the other of its positions in the same manner as in Figs. 1 and 3.

Figs. 5 and 6 show a mercury switch employed as a rheostat to successively by-pass portions of a resistance. Outer and inner shell members in the form of metal tubes 114 and 116 are provided suitably insulated from each other as shown. Enclosed within the outer shell 116 and surrounding the lower part of the inner shell 114 is a porcelain or other body member of heat resisting insulating material 118. This member 118 connects by a suitable channel or orifice 120 with the space within the inner shell 114. Within the body member 118 a channel 122 is provided with a plurality of depressions or pools, each pool being successively slightly higher and grouped circularly about the inner shell 114. Also each pool is provided with a contact connected to a point along the turns of a resistance wire 124. By heating the gas within the inner shell as by a heating resistance 126, the increased pressure drives a quantity of mercury 128 from the inner shell into the channel 122. As the mercury reaches the successive pools, contact is made with different portions of the resistance coil 124 and successively short circuits additional amounts of this resistance. If desired, the connection to the heating coil 126 may include a variable resistance 130 enabling the amount of heat supplied to the heating coil to be controlled to regulate the time necessary to

force the mercury from the inner shell successively into the portions of channel 122 and thus delay the successive short circuiting of the sections of the resistance 124. As shown in Figs. 5 and 6, a contactor in the form of a vertical metal rod 123 extends into each of the depressions in the channelled member 122, serving to connect this depression with a point on resistance 124. Insulating sleeve 133 and insulating disc 135 are added to prevent accidental contact of parts of opposite polarity.

In Figs. 7 and 8 is shown a mercury operated switch generally similar to that shown in Figs. 5 and 6 in that a mercury pool is forced from an inner shell 114 into channels formed within a body member 132 of insulating material and into contact with an outer shell 116. In this form of the invention, however, the channels in member 132 extend radially to enable mercury 128 in any channel to contact the outer shell 116. The space within the inner shell 114 may be heated by a resistance like resistance 126 contacting the wall of the inner shell, the opposite end of the resistance being connected to an insulated terminal 134 extending through an insulating closure for the inner shell 114. When tilted in any direction, as by the rolling or pitching of a ship, one or more channels in member 132 will be maintained filled with mercury and contact with the outer shell will not be broken. By forming a central depression in the insulating body member 132 a quantity of mercury may be provided within the inner shell and surrounding the opening from the inner shell to maintain this opening sealed without any liability of the mercury contacting the outer shell until a material amount of mercury has been forced from the inner shell.

Fig. 9 shows a double pole switch formed from two single pole switches similar to the switch shown in Fig. 3, the two single switches being operated by a single bellows. The central bellows 152 when compressed forces gas from the two chambers formed by the inner shells 10 and 12 and forces the pools of mercury 20 at the inner ends of these shells through an orifice and along grooves formed in insulating bodies 16 so that this mercury 20 will contact the end walls of the outer shells 12. Terminals 22 and 24 are provided on the inner and outer shells 10 and 12 respectively, so that when the mercury pools 20 have been forced from the inner shells the inner and outer shells of each pair are electrically connected. Any type of power circuits may be closed by these simultaneously acting switches.

Figs. 10 and 11 show a form of the invention in which a siphon connection is provided through which mercury is forced from inoperative to operative switch closing position. Two metal tubes 196 and 198, one within the other, are supported in position and suitably insulated from each other as shown. A channelled block of insulating material 200 is inserted within the lower end of the outer tube 196, the block having a central depression and radially extending channels. Extending into the lower end of the inner tube 198 is a siphon 202, the upper end of which is within a pool of mercury 204 and the lower end extends partially within the central depression in block 200. A heating resistance 206 is provided within the upper end of the inner tube 198 so that when the gas within the inner tube is increased in pressure by heating this resistance, or by any other means, mercury 204 will be forced from the inner tube 198 through the siphon 202, which is

preferably of non-conducting material, into the depression and radial channels within block 209. This electrically connects the tubes 196 and 198, both of which are provided with terminals for a power circuit. When the gas within tube 198 again cools the reduced pressure therein draws back the mercury 204 through the siphon and disconnects the two tubes electrically from each other. Above the siphon 202 is a diaphragm 208 having a small central opening therethrough to prevent mercury from entering the upper end of the tube 198 when the unit is turned to any position.

By means of this type of switch employing a siphon 202 the switch is not closed until enough mercury has been forced into the siphon to complete the flow of mercury therethrough. When the flow of mercury through the siphon starts by the greater weight of mercury in the branch leading to the lower opening, the flow will continue to assure completion of the switch closing action.

What I claim is:

1. A fluid operated switch comprising two electrically conducting casings filled with a gas, said casings being one within the other and normally insulated from each other, means to change the pressure of said gas within one of said casings, a connection between said casings, and conducting fluid normally retained within one of said gas filled casings and movable when the pressure of said gas is changed into a position partially filling the other of said casings and electrically connecting terminals secured to said casings.

2. A fluid operated switch comprising two metal casings filled with a gas, said casings being one within the other and normally insulated from each other, means to heat the gas within one of said casings, and a quantity of conducting fluid retained in one of said casings when both casings are at the same temperature, some of said fluid being forced into the second casing when said first casing is heated, whereby said casings are electrically connected when said first casing is heated and a portion of the fluid is forced into the second casing.

3. A fluid operated switch comprising two metal casings one within the other and both casings being filled with a gas and normally insulated from each other, means to change the pressure in one of said gas filled casings, a connection permitting communication between said casings, and a quantity of conducting fluid normally retained within one of said gas filled casings, said fluid being movable when the pressure of said gas is changed to a position electrically connecting terminals secured to said casings.

4. A fluid operated switch comprising two metal casings filled with a gas, said casings being disposed one within the other and normally insulated from each other, means to heat one of said gas filled casings, a connection between said casings, a channelled member of non-conducting material in the other of said casings, and conducting fluid partially in said channelled member and partially filling one of said gas filled casings, whereby when said gas in one casing is heated said conducting fluid is forced from said heated casing to said channelled member and into contact with the other of said casings to electrically connect the two casings.

5. In a fluid operated switch, two casings filled with a gas, one of said casings being metal and connected to an electrical terminal, said casings being positioned one within the other, means to change the pressure of the gas in one of said

casings, a plurality of switch contacts, and a conducting fluid normally retained within one of said casings, said fluid being forced into the other of said casings and successively into electrical connection with said switch contacts when said gas is increased in pressure.

6. A fluid operated switch comprising two casings filled with a gas, one of said casings being metal and connected to an electrical terminal, said casings being positioned one within the other, means to increase the pressure of gas in one of said casings, a member formed of non-conducting material inserted between said casings and having a channel provided with a plurality of depressions, a conducting fluid within said member of non-conducting material and contacting the metal casing, whereby said fluid will be forced successively into said depressions when said gas is increased in volume, and individual terminals dipping into said depressions whereby when said gas is heated said terminals are successively contacted by said conducting fluid.

7. A fluid operated switch comprising two casings, one within the other and the inner casing being formed of conducting material, a gas within said casings, means to change the pressure of the gas in one of said casings, a channelled part of non-conducting material within the outer casing and a quantity of conducting liquid normally within the inner casing, a connection between said casings whereby when the gas pressure within the casing containing the conducting liquid is increased liquid is forced from said inner casing into said channelled part, and electric terminals within said outer casing whereby when liquid is forced into said channelled part said liquid successively connects said electric terminals.

8. A fluid operated switch comprising two metal casings one within the other and both casings being filled with a gas, said casings being normally insulated from each other, means to change the pressure in one of said gas filled casings, a connection permitting communication between the lower ends of said casings, a quantity of conducting fluid normally retained within one of said gas filled casings, said fluid being movable when the pressure of said gas is changed to a position electrically connecting terminals secured to said casings, and means to retain said fluid within the lower end of said inner casing.
